Charles A. Perry - Design for Trade Mark

PATENTED

JUL 10 1866

Des. 2355

Charles A. Perry of Chicago, Ill. assign to
Self & Thomas Dury, of the same place.
Letters Patent No. 2355, Dated July 10, 1866.

Design for Trade Mark for Cigar Cases.

The Schedule referred to in the Letters Patent and making part of this same.

To all whom it may concern:

Be it known that I, Charles A. Perry, of Chicago, in the County of Cook and State of Illinois have invented a new and Ornamental Design for a Trade Mark for Cigar Cases; and I do hereby declare that the following is a full, clear and exact description of the same, reference being had to the accompanying drawings which form part of this Specification. My invention consists in the combination of the words and figures following, that is to say,

The figure of a "Tip" standing in a tipped or inclined position, having the word "Tip" represented thereon, the representation of a cigar and the word case all arranged and engraved in substantially the manner represented in the said drawings, the whole expressing the phrase "The tip-top Cigar Case" which design is intended to be printed or pasted upon cigar cases of a certain pattern or style as a trade mark for the same.

Q.S.2355

2 The stepped position of the top would sufficiently indicate the sound of the word "Ship" without the printing or representing of said word upon the top but for the sake of greater clearness it is so represented.

I claim as my invention and desire to secure by Letters Patent

The Design for a Trade Mark substantially as herein shown and described.
